Primary Examiner—Susan Moon Lee

(57) **CLAIM**

I claim the ornamental design for a heel captivator, according to the present design as shown and described.

DESCRIPTION

FIG. 1 is a back perspective view of a heel captivator.

FIG. 2 is a side perspective view thereof;

FIG. 3 is a front elevation view thereof;

FIG. 4 is a side elevation view thereof, the opposite side being a mirror image;

FIG. 5 is a top plan view thereof; and,

FIG. 6 is a bottom plan view thereof.
